UNITED STATES PATENT OFFICE.

LEVI KIEHL, OF WAYNESBORO, PENNSYLVANIA.

TOOL-REMOVING DEVICE.

Application filed May 5, 1927. Serial No. 189,057.

My invention relates to a device for quickly removing drills, reamers and other tools from the holder of various machines such as, for example, turret lathes, drill presses and the like.

On modern turret lathes, drill presses and the like machines in which tools having tapered shanks are secured, to remove the tool from the socket of the holder it is customary to use a hand drift or tool removing instrument and hammer and in using these it is necessary for the operator to hold the drift in one hand and strike the same with the hammer held in the other hand, then lay down the hammer and drift and remove the tool. Often the tool falls out of the holder and is lost or falls into some inaccessible spot, requiring considerable time to recover the same.

It is an object of the invention to apply a simple device to a socket by means of which a tool may be removed with one hand from such socket while the other hand may be used to grip the tool being removed, all as will be hereinafter more fully described and claimed.

Referring to the drawings, which are made a part hereof and in which similar reference characters indicate similar parts:

Figure 1 is a side elevation of a holder equipped with my invention,

Figure 2, a part side elevational part sectional view of the structure shown in Fig. 1, and at right angles thereto,

Figure 3, a section on the line 3-3 of Fig. 2,

Figure 4, a detail of the sleeve or cylinder shown in Fig. 2, and

Figure 5, an edge view of the specific drift.

In the drawings, reference character 10 indicates the holder of a turret lathe, drill press or other machine, such holder being provided with a longitudinally disposed tapered tool receiving recess or socket 11 for the tapered shank of a tool 12. The holder 10 has a transverse opening or slot 13 formed in communication with the upper end of the tapered opening 11 and at one end of said transverse opening the holder is provided with a cylindrical recess 14 into which is threaded a drift spring cylinder 15 held in position by a lock nut 16. The threaded end of the cylinder 15 is provided

with slots 17 at each side of the same which is adapted to receive the slidably mounted tapered head 18 of a drift or pin, said drift or pin having a substantially rectangular shank 19 formed integrally with said tapered head which has its outer end extending through the end of the cylinder 15.

The shank 19 of the drift is provided with a transversely disposed pin 20 which is slightly shorter in length than the internal diameter of the cylinder 15 and said shank 65 is also provided with a longitudinally disposed slot 21 in spaced relation to the pin 20 and through which extends a pin 22 carried by the cylinder 15. A spring 23 is disposed between the pin 20 carried by the shank 70 of the drift and the pin 22 carried by the cylinder, so that they will be normally held in spaced relation, as shown in Fig. 2, with the head 18 retracted or out of engagement with the end of the tool 12. The outer extremity of the cylinder 15 is provided with a polygonal wrench engaging portion 24 by means of which the cylinder may be rotated for adjusting the position of the drift and for tightening the cylinder in the holder 10. 80

On account of the threaded end of the drift spring cylinder and lock nut, the cylinder may be adjusted so that the drift may be held in proper relation to the end of the tool 12, whereupon, upon the drift being 85 struck with a hammer at the outer end of the shank 19, the tool 12 will be forced from its socket and all that is necessary to perform this operation is the mere striking of the end of the drift with a hammer. 90

My device may be applied to a tool holder at a very small cost and will result in the saving of considerable time as well as the elimination of numerous unnecessary time consuming motions. 95

It will be obvious to those skilled in the art that various changes may be made in my device, without departing from the spirit of my invention, and I, therefore, do not limit myself to what is shown in the 100 drawings and described in the specification, but only as set forth in the appended claims.

Having thus fully described my invention, what I claim as new and desire to secure by Letters Patent is:

1. A tool holder having a socket for reception of a tool, said tool holder having a transverse slot communicating with the

socket, a drift mounted longitudinally in said transverse slot and movable across the end of the tool socket, and spring means for holding said drift in retracted position, substantially as set forth.

2. A tool holder having a socket for reception of a tool, said tool holder having a transverse slot communicating with the socket, a drift mounted longitudinally in 10 said transverse slot across the end of said socket, spring means for holding said drift in retracted position, and means adjustable transversely of said tool holder for supporting said drift, substantially as set forth.

15 3. A tool holder having a socket for the reception of a tool, a tool removing member mounted on said holder and adapted to be operated for removing the tool from its socket, automatically operating means for 20 retracting said tool removing member and for maintaining the same in retracted position, and adjustable means mounted on said tool holder for supporting said tool removing member, substantially as set forth.

25 4. A tool holder having a socket for the reception of a tool, a tool removing member mounted on said holder and adapted to be operated for removing the tool from its socket, and a housing for said tool removing

member detachably mounted directly on said holder, substantially as set forth.

5. A tool holder having a socket for the reception of a tool, a tool removing member transversely mounted on said holder and adapted to be operated for removing the tool from its socket, a housing for said tool removing member detachably mounted directly on said holder in transverse position, and automatically operating means in said housing for retracting said tool removing member and for maintaining the same in retracted position, substantially as set forth.

6. A tool holder having a socket for the reception of a tool, a tool removing member mounted transversely on said holder and adapted to be operated for removing the tool from its socket, a housing for said tool removing member detachably mounted on said holder, and a spring in said housing and engaging said housing and said tool removing member and maintaining said tool removing member in retracted position, substantially as set forth.

In witness whereof, I have hereunto set my hand at Waynesboro, Pennsylvania this 4th day of May, A. D. nineteen hundred and twenty-seven.

LEVI KIEHL.
